UNITED STATES PATENT OFFICE.

HUBERT FRITZ NEUSS, OF AIX-LA-CHAPELLE, GERMANY.

SAFETY-PIN.

SPECIFICATION forming part of Letters Patent No. 334,541, dated January 19, 1886.

Application filed August 11, 1885. Serial No. 174,095. (No model.) Patented in Germany May 23, 1883, No. 25,701.

To all whom it may concern:

Be it known that I, HUBERT F. NEUSS, of Aix-la-Chapelle, Germany, have invented an Improved Safety-Pin, of which the following 5 is a full, clear, and exact description, reference being made to the accompanying drawings, and for which I have obtained Letters Patent in Germany, No. 25,701, dated May 23, 1883.

10 Figure 1 shows a pin and its point-protecting collar, said collar being removed from said pin, and being partly in section. Fig. 2 shows a side view of the pin and its collar, the latter being removed from the pin. Fig. 3 is a sec- 15 tional view of the collar placed on a pin. Fig. 4 is a cross-section on the line $x-x$, Fig. 2.

This invention relates to improvements in safety-pins, in which the point of the pin is 20 protected by being surrounded by a detachable collar or tube.

It consists in compressing one end of a small metallic tube at one or more points of its circumference, which compressions decrease the size of its bore, and thus allow the conical end 25 of the pin to be wedged between said compressions.

In the drawings, A represents the pin, the main part of which fits the mouth end a of a thin metallic cylindrical tube or collar, B.

The other end of this tube—that is, the end to 30 which the head D is attached—has one or more compressions, E, or flat parts, as shown in Fig. 4. These compressions destroy the round bore of the tube, making it at one end of the 35 form shown in Fig. 4. The mouth end a of the tube B is milled out flaring, so as to facilitate the insertion of the pin.

When the conical or pointed end of the pin is to be protected, it is inserted into the tube B until it strikes the flat face E, when by a 40 slight turn of the pin it is firmly held by said compressions. The pin is removed by turning it in the opposite direction. The advantage of this method of forming the collar B is, 45 that a plain cylindrical tube can be used for it by simply compressing one of its ends at one or more places, which is a much more simple and inexpensive method of forming said collar than by reaming or otherwise.

I claim—

The combination of the collar B, which is 50 compressed or flattened in one or more places, E, with the pin A, substantially as herein shown and described.

HUBERT FRITZ NEUSS.
